EGG FRESHNESS TESTER

George E. Carlson, Minneapolis, Minn., assignor to Minnesota Rubber Company, Minneapolis, Minn., a corporation of Minnesota

Filed Apr. 27, 1961, Ser. No. 64,928

Term of patent 14 years

(Cl. D52—6)

FIG. 1.

FIG. 2.

FIG. 3.

FIG. 4.

FIG. 1 is a front elevational view of an egg freshness tester, showing my new design;

FIG. 2 is a side elevational view thereof;

FIG. 3 is a top plan view thereof; and

FIG. 4 is a bottom plan view thereof.

A side elevational view of my egg freshness tester taken from the side opposite that shown in FIG. 2 is essentially the same in appearance as FIG. 2.

I claim:

The ornamental design for an egg freshness tester, as shown and described.
